[57] CLAIM

The ornamental design for a holder for testing an integrated circuit chip, as shown.

DESCRIPTION

FIG. 1 is a top, front, and right side perspective view of a holder for testing an integrated circuit chip showing my new design;

FIG. 2 is a bottom, rear, and left side perspective view thereof;

FIG. 3 is a left side elevational view thereof, the right side being a mirror image thereof;

FIG. 4 is a rear elevational view thereof; and

FIG. 5 is a front elevatioal view thereof.

FIG. 1

FIG. 2

FIG. 3

FIG. 4

FIG. 5
